(57) **CLAIM**

The ornamental design for a foldable utility knife, as shown and described.

DESCRIPTION

FIG. 1 is a perspective view of a folding utility knife showing my new design;

FIG. 2 is a top plan view thereof;

FIG. 3 is a right side elevation view thereof;

FIG. 4 is a front elevation view thereof;

FIG. 5 is a rear elevation view thereof;

FIG. 6 is a bottom plan view thereof;

FIG. 7 is a left side elevation view thereof;

FIG. 8 is a right side elevation view thereof, showing it in a partially folded position; and,

FIG. 9 is a right side elevation view thereof, showing it in a folded position.

The broken line showing of the utility knife handle is included for the purpose of illustrating environmental structure and forms no part of the claimed design.
